UNITED STATES PATENT OFFICE.

HARRY A. JOST, OF CHICAGO, ILLINOIS.

CUE-TIP.

1,199,082.

Specification of Letters Patent. Patented Sept. 26, 1916.

Application filed February 15, 1915. Serial No. 8,126.

To all whom it may concern:

Be it known that I, HARRY A. Jost, a citizen of the United States of America, and a resident of Chicago, in the county of Cook, 5 State of Illinois, have invented certain new and useful Improvements in Cue-Tips, of which the following is a specification.

This invention relates to detachable tips for billiard cues, and has for its object to 10 provide a simple and efficient structural formation and association of parts, whereby said parts are connected in a secure and substantial manner when assembled, and are capable of ready disassembly for the 15 replacement of a worn or defective part, all as will hereinafter more fully appear.

In the accompanying drawings:—Figure 1 is a perspective view of the cue tip parts in a detached condition. Fig. 2, is a central 20 longitudinal section. Fig. 3 is a perspective view of the cue tip parts in an assembled condition.

Similar reference numerals indicate like 25 parts in the several views.

Referring to the drawings, 1 designates the point portions of the cue stock formed with a cylindrical axial stud or dowel 2 at its extreme end as shown.

30 3 designates an intermediate attaching head formed of celluloid or the like and fixedly connected to the stud or dowel 2 of the stock in any usual manner, preferably by a cylindrical axial socket 4 in the head 3 adapted to receive said stud or dowel and 35 have a driving fit therewith. The separate attaching head 3 is intended to afford a more substantial and durable means of attachment for the present detachable tip, than would be afforded by the wood of a billiard cue stock.

5 designates a cylindrical axial stud arranged at the end of the attaching head 3 opposite to the socket 4, aforesaid.

6 designates the carrying ring or annulus for the leather cue-tip 7. Said annulus is formed of vulcanized fiber or the like and 45 its cylindrical bore 8 is adapted to have a drive fit with the axial stud 5 of the attaching head 3, aforesaid.

9 designates a thin annular metal band or thimble, the lower portion of which is permanently embedded in the annulus 6, aforesaid, while its upper portion is formed with a taper edge adapting the same to be driven into the material of the leather tip 7, to secure the described parts together in a secure 55 and substantial manner.

Having thus fully described my said invention what I claim as new and desire to secure by Letters Patent is:—

A separable tip for billiard cues, comprising a leather tip portion, a carrying annulus, an annular thimble partly embedded in said annulus and having an annular portion projecting from said carrying annulus, said annular projecting portion having a tapering 60 form in cross-section adapting it for driving engagement in the tip portion, and an attaching head secured to the cue-stock and having a central stud adapted for engagement in the bore of the carrying annulus, 65 substantially as set forth.

Signed at Chicago, Illinois, this 13th day of February, 1915.

HARRY A. JOST.
